UNITED STATES PATENT OFFICE

102,392

DESIGN FOR A FUEL SUPPLY UNIT FOR OIL BURNERS

Herbert C. Osborne, Racine, Wis., assignor to
Webster Electric Company, Racine, Wis., a cor-
poration of Wisconsin

Application October 26, 1936, Serial No. 65,503

Term of patent 14 years

To all whom it may concern:

Be it known that I, Herbert C. Osborne, a citizen of the United States, residing in Racine, in the county of Racine and State of Wisconsin, have invented a new, original, and ornamental Design for Fuel Supply Units for Oil Burners, of which the following is a specification, reference being had to the accompanying drawing forming part thereof.

Fig. 1 is a top plan view of a fuel supply unit for oil burners embodying the design;

Fig. 2 is a side elevation taken from the side which is toward the bottom in Fig. 1;

Fig. 3 is an end elevation taken from the end which is toward the elevation in Fig. 1, the other end being similar in appearance;

Fig. 4 is a side elevation taken from the side which is toward the top in Fig. 1.

I claim:

The ornamental design for a fuel supply unit for oil burners, as shown.

HERBERT C. OSBORNE.
